FRED G. GARDNER, OF NEW YORK, N. Y., ASSIGNOR TO WESTERN ELECTRIC COMPANY, INCORPORATED, OF NEW YORK, N. Y., A CORPORATION OF NEW YORK.

SIGNALING SYSTEM.

1,380,374.

Specification of Letters Patent. Patented June 7, 1921.

Application filed November 21, 1919. Serial No. 339,766.

To all whom it may concern:

Be it known that I, FRED G. GARDNER, a citizen of the United States residing at New York, in the county of New York, State of New York, have invented certain new and useful Improvements in Signaling Systems, of which the following is a full, clear, concise, and exact description.

This invention relates to signaling systems and more specifically to signaling systems which are especially applicable to signaling on composite telegraph and telephone circuits.

In certain telephone systems, particularly those in which telegraph and telephone circuits are combined, it is desirable to use for signaling purposes, currents of different frequencies. Especially in composite telegraph and telephone systems it is desirable to use high frequency currents of approximately 133 cycles per second for the purpose of operating a signal in connection with the telephone service without interfering with the operation of the telegraph service. Since the standard type of signal used in connection with telephone lines is adapted to respond only to a current of a much lower frequency, such as 16½ cycles per second, it is necessary to provide some means for translating the high frequency current into a current of such low frequency as will properly operate the telephone signaling device.

In signaling systems of this nature now in use, it has been found feasible to employ a translating means selectively responsive to the relatively high frequency currents transmitted over the line, such means being unresponsive to the relatively low frequency currents used for telegraph service or impressed upon the line by the actuation of the switchhooks on the connected telephone lines. However, it has been found somewhat difficult to provide a telephone signaling device which is unresponsive to the currents of the latter mentioned characters, while remaining reliably responsive to the translated currents. Although the desired result may be obtained in a particular instance by means of accurate and refined adjustments of the signaling control device, such adjustments are very difficult to obtain as well as to maintain when once secured, since the electrical characteristics of the associated line circuit are unstable.

The object of the present invention is to

provide an improved arrangement of this nature readily applicable to systems of this character, in which the false or improper operation of the telephone signal control means is prevented.

To obtain this object in accordance with a feature of the invention, the telephone signal control means is normally disassociated from the line circuit and is associated therewith only during the response of the translating means to the current of the proper frequency when received over the line circuit.

This and other features not specifically mentioned above, will more clearly appear from the following specification and the accompanying drawing in which the figure shows diagrammatically sufficient portions of one end of a telephone line circuit equipped with a portion of a composite ringer circuit and an associated link circuit to properly illustrate the invention.

In the drawing, a telephone line circuit A terminates in a jack 1 at a central office or switchboard. Line conductors 4 and 5 of such line circuit may be assumed as extending to the line side of a regular composite circuit equipped with a composite ringer circuit. The complete composite ringer circuit is not shown since it is not essential to a proper understanding of the invention and may be of any suitable type. A relay 6 bridged across conductors 4 and 5 of the outer section of the line circuit controls a relay 8 which controls a switching relay 7 for disconnecting the inner and outer sections of the line circuit and for connecting the source of alternating current preferably of 16½ cycles per second, to the inner section. The relay 8 also controls a relay 9 for controlling the continuity of a bridge across the conductors of such inner section of the line circuit. Relay 10 included in such bridge is adapted to respond to the current supplied from the source connected to the inner section by the relay 7 and controls the illumination of the line signal lamp 13, associated with the jack 1, through the medium of a locking relay 12. A link circuit B of any usual type, equipped with a drop or other signaling device 3, bridged across the conductors thereof, and terminating in a plug 2, is provided for connection with the jack 1. A sleeve relay 11, associated with the line circuit A, is responsive to such inter-

connection to control another gap in the bridge circuit including the relay 10, and to render the line signal ineffective.

It is thought that the invention may be 5 fully comprehended from the following description of the operation of the system shown on the drawing.

Assuming that the current, having a frequency of approximately 133 cycles per second, is being transmitted over the line conductors 4 and 5 and flows through the windings of relay 6, relay 6, responding thereto, opens the circuit of and causes the release of 10 normally operated relay 8. Relays 7 and 9 thereupon operate over a circuit extending from battery through the windings of relays 7 and 9 in parallel to the normal contact of relay 8 and thence to ground. Relay 7, in 15 operating, disconnects the conductors of the inner section of the line circuit extending to the jack 1, from the corresponding conductors 4 and 5 of the outer section extending to the distant station, and also connects to such inner section a source of signaling 20 current of a frequency of 16 $\frac{2}{3}$ cycles per second, such as is usually employed in operating telephonic signaling apparatus. Relay 9, in operating over an obvious circuit, places the winding of relay 10 in bridged 25 relation to the conductors of the inner section. Relay 10 operates over a circuit extending from the source of alternating current through the lower alternate contact of relay 7, the left-hand contact of relay 11, the contact of relay 9, the winding of relay 10 and the upper alternate contact of relay 7 to ground. Relay 12 then operates over 30 an obvious circuit, the closure of its left-hand contact completing a locking circuit there- 35 for and the closure of its right-hand contact causing the illumination of the line lamp 13. Upon the cessation of the incoming signaling current present in the conductors 4 and 5, relay 6 releases, causing the 40 operation of relay 8 and the consequent release of relays 7, 9 and 10. Thus the source 45 of 16 $\frac{2}{3}$ cycle alternating current is disconnected from the inner section of the line circuit, such section is reassociated with the 50 outer section and the bridge including the relay 10 is again interrupted. However, line lamp 13 remains lighted due to the locked condition of relay 12.

In response to the illumination of lamp 55 13 the operator inserts plug 2 into jack 1, whereupon relay 11 operates over a circuit established from battery through the sleeve contacts of plug 2 and jack 1 and the winding of relay 11 to ground. The opening of 60 the right-hand contact of relay 11 releases relay 12 thereby extinguishing the line lamp 13. The left-hand contact of relay 11, in opening, introduces a second break in the bridge including the winding of ringing 65 response relay 10. Therefore in case ring-

ing current of 133 cycles per second is transmitted over the line conductors 4 and 5 while the plug 2 remains in the jack 1 as in the case of a recall from the distant station, relays 6, 7, 8 and 9 function as before, but 70 relay 10 does not respond due to the fact that the bridge therefor is opened at the left-hand contact of relay 11. Thus the drop or other telephonic signaling device 3 associated with the connecting link circuit 75 B, is operated over a circuit established from the source of alternating current of 16 $\frac{2}{3}$ cycles per second, through the lower alternate contact of relay 7 the ring contacts of jack 1 and the plug 2, the winding of the 80 drop or other signaling device 3, the tip contacts of plug 2 and jack 1, and the upper alternate contact of relay 7 to ground. Upon the removal of the plug 2 from the jack 1, all the system restores to normal as shown 85 in the drawing.

It will be evident that with the present invention the usual telephonic line signaling device is rendered independent of all signaling currents which may be received 90 over the line circuit except those which cause the operation of the translating means.

What is claimed is:

1. In a signaling system a line circuit comprising inner and outer sections, means 95 associated with the outer section and responsive to signaling current received thereover, means controlled thereby for disassociating the sections and connecting a source of signaling current to the inner section, 100 additional means also controlled by the second-mentioned means to associate with the inner section means responsive to current flowing from such source, and a signal controlled thereby.

2. In a signaling system a line circuit comprising inner and outer sections, a source of signaling current, a signal control means responsive thereto, means for disassociating the sections and for associating the source 110 of current with the inner section, means for associating the signal control means with the inner section, and means associated with the outer section responsive to signaling current received thereover for controlling the 115 first and second mentioned means.

3. In a signaling system a line circuit, a source of current, means responsive thereto, a signaling device controlled thereby, and means associated with the line circuit and 120 responsive to signaling current received thereover for simultaneously localizing a section of such line circuit and associating the source of current and the signal control means with such localized section.

4. In a signaling system a line circuit comprising normally interconnected inner and outer sections, a source of current, a signal control means responsive to current flowing therefrom, and means associated 130

- with the outer section and responsive to signaling current received thereover to disconnect the sections and to associate the source of current and the signal controlling means 5 with the inner section and to restore the sections, the source of signaling current and the signal controlling means to normal upon the cessation of the current in the outer section.
- 10 5. In a signaling system a line circuit, a relay permanently associated therewith and responsive to periodically varying current of one frequency, a source of periodically varying current of another frequency, a sec-
- ond relay responsive to current flowing 15 therefrom for controlling a signaling device, a third relay for interrupting the continuity of the line circuit and associating the source with an isolated portion thereof, a fourth relay for associating the second relay 20 with the isolated portion of the line circuit and a normally operated relay controlled by the first relay to simultaneously control the third and fourth relays.

In witness whereof, I hereunto subscribe 25 my name this 18th day of November A. D., 1919.

FRED G. GARDNER.
